CLAIM

The ornamental design for a liner, as shown and described.

DESCRIPTION

FIG. 1 is a perspective view of the liner of the invention.

FIG. 2 is a plan view from the top of the liner shown in FIG. 1.

FIG. 3 is a plan view from the bottom of the liner shown in FIG. 1.

FIG. 4 is an elevational view of the front of the liner shown in FIG. 1.

FIG. 5 is an elevational view of the rear of the liner shown in FIG. 1; and,

FIG. 6 is an elevational view of the side of the liner shown in FIG. 1, the opposite side is identical.
